[57] CLAIM

The ornamental design for a power unit for paint roller, substantially as shown.

DESCRIPTION

FIG. 1 is a side elevational view of a power unit for paint roller showing our new design;

FIG. 2 is a top plan view thereof;

FIG. 3 is a side elevational view thereof shown from the side opposite FIG. 1;

FIG. 4 is a side elevational view thereof shown from the right side of FIG. 1;

FIG. 5 is a bottom plan view thereof;

FIG. 6 is a side elevational view thereof shown from the right side of FIG. 1.

The broken line fragmentary showing of a hose and cord in most views is for illustrative purposes only and forms no part of the claimed design.
